UNITED STATES PATENT OFFICE.

ALEXANDER M. ALEXANDER, OF BEVERLY, MASSACHUSETTS, ASSIGNOR TO UNITED SHOE MACHINERY COMPANY, OF PATERSON, NEW JERSEY, A CORPORATION OF NEW JERSEY.

METHOD OF MAKING KNIVES.

1,003,409.

Specification of Letters Patent. Patented Sept. 19, 1911.

Application filed January 7, 1910. Serial No. 536,835.

To all whom it may concern:

Be it known that I, ALEXANDER M. ALEXANDER, a citizen of the United States, residing at Beverly, in the county of Essex and State of Massachusetts, have invented 5 certain Improvements in Methods of Making Knives, of which the following description, in connection with the accompanying drawings, is a specification, like reference characters on the drawings indicating like parts in the several figures.

This invention relates to a method of making cylindrical knives. These knives which have the cutting edge formed upon 15 one end of a cylinder are used in various arts, the illustrated knife, which the method herein described is especially intended to produce, being employed in a machine for skiving the parts of boot and shoe uppers 20 such as shown in my co-pending application, Ser. No. 522,905, filed October 16, 1909.

Cylindrical knives have long been employed in skiving machines, but owing to the 25 great cost of the knives these machines have not come into very extensive use. There are, however, some advantages in skiving with a cylindrical knife which make skiving machines employing such knives desirable 30 in the manufacture of boots and shoes, and in order therefore that these advantages may be generally availed of without the accompanying excessive cost of the skiving knives, 35 an object of this invention is a method of making cylindrical knives, especially adapted for use in skiving machines, by which these knives may be produced at a low cost.

To this end the method contemplates the 40 novel procedure hereinafter set forth by which a knife having a true cylindrical form, which is of a size to fit accurately the holder for which it is made, and which is properly hardened and tempered may be easily and quickly produced.

45 Where accuracy of form and fit has been especially desirable, as in skiving machines, cylindrical knives have usually been made heretofore by forging a blank and then milling the blade out of the blank. Knives thus produced are obviously comparatively expensive. By the method of this invention a band of steel of the proper composition and length is first rolled into the desired cylindrical form, is then confined in a holder constructed to maintain this form and while

confined in this holder is hardened throughout that portion which, upon successive grindings, will furnish the successive cutting edges.

In Figure 1 of the accompanying drawings is shown a knife of the type intended to be produced by this method; in Fig. 2 is shown the holder in which the knife is confined for the hardening operation after it has been rolled into its shape, the holder 60 in this figure being shown with the parts in the relative positions into which they are put when the part of the knife to be hardened is to be immersed in the heating bath; Fig. 3 is a section through the knife holder 65 showing the parts in the relative position into which they are put when the knife is to be immersed in the hardening bath.

The knife 2 shown in Fig. 1 is formed of a ribbon or band of steel of suitable composition, the band being preferably of uniform composition throughout. This band having been cut to the proper length is first rolled by any suitable rolling machine into the desired cylindrical form, provision being 70 made in measuring the original length for a slight contraction in hardening and tempering. The band of steel is preferably rolled into its cylindrical form while in its untempered condition. Having been rolled 75 into cylindrical form, the knife is placed in the holder shown in Figs. 2 and 3, this holder being adapted to engage the knife both on its outside and on its inside surfaces, 80 as shown especially in Fig. 3. The holder comprises a ring 4 having an annular socket 6 which receives the knife 2 and in which the knife is confined by a second ring 8 milled to fit within the knife 2 when it is 85 in the socket 6 and to rest upon the bottom 90 of said socket. The ring 8 is of such vertical dimension that its upper surface lies flush with the upper surface of the ring 4 when it is in the socket 6. A bail 10 having 95 ears which receive trunnions 12 upon the 100 ring 4 is used by the operator to support and lift the ring during the heating and hardening operations. The ring 4 is also provided with an eye piece 14 so located that the operator may engage it with a hook and turn 105 the ring over after the heating operation to cause the ring to assume the position shown in Fig. 3 for the hardening operation.

The method of procedure in the heating and hardening operations is as follows: 110

The parts being in the position shown in Fig. 2, the exposed portion of the knife 2 is immersed in a lead heating bath, the ring itself being only very slightly submerged in 5 the bath. The knife is held in the bath until its exposed portion is heated to the desired hardening temperature, the portions of the knife immediately adjacent to the exposed portion being heated by conduction through 10 the rings 4 and 8. After the knife is heated to the desired hardening temperature, the holder is taken from the heating bath and the operator engages the eye 14 with a hook or other tool and turns the holder into the 15 position shown in Fig. 3. The holder and knife are then immersed in the hardening bath which is preferably an oil bath. It will be seen that the holder strikes the hardening bath first and that thus the confined 20 portion of the knife is first cooled and that the unconfined portion is cooled gradually, the part of the exposed portion of the knife nearest the confined portion being first cooled and then the succeeding parts until the outer 25 edge of the unconfined portion is reached. This procedure keeps the knife from assuming a cannon mouth form. After the knife has been heated and hardened in the manner described it is removed from the 30 holder and put into a tempering bath and the hardness drawn to the required degree.

Having described my invention, what I claim as new and desire to secure by Letters Patent of the United States is:—

35 1. That improvement in the art of making

cylindrical knives which consists in rolling into the desired cylindrical form a band of steel of the proper composition and length, confining a marginal portion of the blank thus formed in a holder constructed to maintain the cylindrical form of the blank, immersing the unconfined portion only of the blank in a heating bath, and then reversing the holder to bring the unconfined portion of the blank above the holder and immersing the holder and blank in a hardening bath.

2. That improvement in the art of making cylindrical knives which consists in rolling into the desired cylindrical form a band of 40 steel of the proper composition and length, confining a marginal portion of the cylindrical blank thus formed in a holder constructed to maintain the cylindrical form, immersing the unconfined portion of the 45 blank in a lead heating bath and then immersing the holder and blank in a hardening bath in such manner that the confined portion of the blank is first cooled and that the unconfined portions which are heated to 50 higher temperatures are cooled successively toward the edge which is to form the cutting edge.

In testimony whereof I have signed my name to this specification in the presence of 55 two subscribing witnesses.

ALEXANDER M. ALEXANDER.
